UNITED STATES PATENT OFFICE

2,583,500

CATHODE-RAY TUBE

Frederick H. Townsend, Cambridge, England, assignor to Cathodeon Limited, Cambridge, England, a British company

Application November 25, 1949, Serial No. 129,232
In Great Britain November 25, 1948

3 Claims. (Cl. 313—82)

1

The present invention relates to cathode ray tubes having magnetic deflection, such as are used in television apparatus.

In the manufacture of cathode ray tubes, considerable difficulty is experienced in mounting the electron gun in accurate alignment with the axis of the tube so that the undeflected electron beam will be emitted along a path which is co-axial with the neck portion of the tube and will be equally spaced from the magnetic deflection coils positioned around that neck portion. Due to inevitable slight inaccuracies in manufacture, the undeflected path of the emitted electrons is generally not co-axial with the neck portion, but is inclined to the axis. Therefore, the focussing coil surrounding the neck of the tube generally has to be inclined in order to compensate for the inclination of the beam by deflecting the beam so as to cause it to follow a path which is parallel to the axis of the tube. However, since thereby the redirected beam is displaced to one side of the tube axis and thus lies nearer to the deflection coil on one side of the tube neck than to the deflection coil on the other side, the raster produced by the beam is distorted.

The present invention has for its object to provide a construction of cathode ray tube and method which overcomes these difficulties and enables cathode ray tubes to be manufactured on a mass production scale without the imposition of very close tolerances with regard to the construction and location of the electron gun.

In order to avoid the raster distortion referred to, it is essential that the electron beam enter the field of the deflection coil yoke centrally therewith. To this end, according to the invention, a diaphragm is mounted within the neck of the cathode ray tube, in the plane at which the beam enters the deflection field, that is after the beam has passed through the focussing field but before it passes through the deflection field. The diaphragm has an aperture which is carefully located on the axis of the tube neck.

The electron gun is so designed that the beam of electrons produced is divergent, preferably widely divergent. The gun is then so located that the axis of its emergent beam is as nearly coincident with the axis of the tube neck as is reasonable by normal production methods and is directed towards the aforementioned diaphragm.

Before reaching the diaphragm, the beam passes through the focussing field and, owing to the effects of that field, the beam becomes

2

convergent. As, however, the diaphragm is located only a short distance beyond the exit of this focussing field, the beam still has a diameter which is large relative to the diameter of the aperture. This diaphragm therefore allows only that part of the electron beam to pass which is coincident with the aperture, and as a result of the careful location of this aperture the electrons emerging therefrom, which together form the operating electron beam of the tube, enter the deflection field on the axis of the tube neck. It remains only to locate the deflection coil yoke externally to the tube neck and centrally aligned with respect thereto, and the required result is achieved of obtaining a beam of electrons which enters the deflection field on the axis thereof whereby the raster distortions hitherto experienced may be avoided.

By this means, provided that the misalignment of the electron beam prior to its incidence upon the diaphragm is not so great that the portion of the beam allowed to pass through the aperture is selected from the edge of the beam where the electron density is lower and less uniform than it is in the paraxial portion of the beam, the effects of such misalignment, be it due to mechanical misalignment of the electron gun or to the presence of asymmetrical fields having a deflecting action on the beam, are largely negated.

In order that the invention may be more clearly understood, an embodiment thereof is diametrically shown in the accompanying drawing which illustrates an application of the invention to an otherwise conventional type of cathode ray tube for television reception, having an envelope 1 comprising coaxial neck and bulb portions 2 and 3 respectively, the neck 2 containing an electron gun 4 of conventional construction comprising a cathode 5, a modulating grid 6 and an anode 7 mounted in the end of the neck and directed towards a fluorescent screen 8 provided on the end face of the bulb 3 and upon which the raster produced by the beam generated by the gun is traced. A conventional focussing coil 9 and deflection coil yoke 10 are fitted around the neck 2, and each aligned coaxially thereto. 11 indicates the customary internal conductive wall coating of the bulb connected to anode potential.

The gun 4 is located in the neck 2 so that the axis of its emergent beam, indicated at 12, is as nearly coincident with the axis of the neck as is reasonable by normal methods of production of the tube. The gun is designed so as

to produce a wide-angle divergent electron beam 12. A diaphragm 13 is mounted in the neck and has a small aperture 14 therein which is carefully located on the axis of the neck, the diaphragm being disposed between the fields produced by the coil 9 and yoke 10 so that it lies in the path of the beam after it leaves the focussing field and before it enters the deflection field.

In the operation of the tube, the divergent beam 12 emitted from the gun 4 passes through the focussing field of the coil 9 and is made convergent, as indicated at 15, by the effects of that field. As the diaphragm 13 is located only a short distance beyond the exit of the focussing field, the convergent beam 15 still has a large diameter relatively to the diameter of the aperture 14, and consequently the diaphragm 13 allows only that part of the beam 15 which is coincident with the aperture 14 to pass therethrough. By reason of the careful location of this aperture on the neck axis, the emergent beam 16 enters the deflection field of the yoke 10 on the axis of the neck 2, and thus on the axis of the yoke 10 and deflection field, as a limited narrow angle convergent electron beam 16 which thus traces an undistorted raster on the screen 8.

Although the invention has been illustrated in an application to a television-receiving cathode ray tube of otherwise conventional construction, the described embodiment is merely given as an example, since the invention is equally applicable to any type of cathode ray tube in which the generation of a distortion-free deflection pattern of a scanning electron beam is necessary.

I claim:

1. A cathode ray tube having an envelope including a neck, an electron gun including a cathode and electrode means for forming a divergent beam of electrons from said cathode, said gun being mounted and aligned in said neck to direct said beam substantially coaxially along said neck, a focussing coil coaxially mounted on said neck for focussing said divergent beam into a convergent beam, a diaphragm structurally independent of said gun mounted in and located with reference to said neck a short distance beyond said coil for intercepting said convergent beam emerging from the focussing field of said coil, said diaphragm having a small aperture therein accurately located on said neck axis to select from said convergent beam and allow to pass through said aperture a paraxial portion of said beam coincident with said aperture, whereby the selected beam emergent from said aperture of said diaphragm follows a path coincident with said neck axis, and deflecting coil means mounted coaxially on said neck beyond said diaphragm for deflecting said emergent beam to form a raster.

2. A cathode ray tube having an envelope including a neck, an electron gun including a cathode and electrode means for forming a divergent beam of electrons from said cathode, said gun being mounted and aligned in said neck to direct

said beam substantially coaxially along said neck, a focussing coil coaxially mounted on said neck for focussing said divergent beam into a convergent beam, a plane diaphragm structurally independent of said gun mounted in and located with reference to said neck perpendicularly to said neck axis a short distance beyond said coil for intercepting said convergent beam emerging from the focussing field of said coil, said diaphragm having a small circular aperture therein accurately located on said neck axis to select from said convergent beam and allow to pass through said aperture a paraxial portion of said beam coincident with said aperture, whereby the selected beam emergent from said aperture of said diaphragm follows a path coincident with said neck axis, and deflecting coil means mounted coaxially on said neck beyond said diaphragm for deflecting said emergent beam to form a raster.

3. A cathode ray tube having an envelope including a neck, an electron gun including a cathode and electrode means for forming a divergent beam of electrons from said cathode, said gun being mounted and aligned in said neck to direct said beam substantially coaxially along said neck, a focussing coil coaxially mounted on said neck for focussing said divergent beam into a convergent beam, a diaphragm structurally independent of said gun mounted in and located with reference to said neck for intercepting said convergent beam emerging from the focussing field of said coil at a short distance beyond the zone of inflection of said beam, said diaphragm having a small aperture therein accurately located on said neck axis to select from said convergent beam and allow to pass through said aperture a paraxial portion of said beam coincident with said aperture, whereby the selected beam emergent from said aperture of said diaphragm follows a path coincident with said neck axis, and deflecting coil means mounted coaxially on said neck for deflecting said emergent beam to form a raster, said deflecting means being located such that said diaphragm lies in the plane at which said emergent beam enters the deflection field of said deflecting means.
